(57) **CLAIM**

The ornamental design for a string lamp, as shown and described.

DESCRIPTION

FIG. 1 is a perspective view of a string lamp showing my new design;
FIG. 2 is another perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof; and,
FIG. 9 is an enlarged view of portion 9 shown in FIG. 1. The string lamp is shown with a symbolic break in its length and the appearance of any portion of the string lamp between the break lines form no part of the claimed design. The regularly spaced broken lines depict portions of the string lamp that form no part of the claimed design and the dot dash broken lines depict the area of enlargement shown in FIG. 9.
